Mrs De LANA SHEPLIE

UNITED STATES PATENT OFFICE.

DE LANA SHEPLIE, OF BOSTON, MASSACHUSETTS, ASSIGNOR TO HERSELF
AND GEORGE E. HENRY, OF SAME PLACE.

IMPROVEMENT IN BINDING AND WIRING HAT-BRIMS.

Specification forming part of Letters Patent No. 152,016, dated June 16, 1874; application filed
January 23, 1874.

To all whom it may concern:

Be it known that I, Mrs. DE LANA SHEPLIE, of Boston, in the county of Suffolk and State of Massachusetts, have invented a new and useful Improvement in Machinery for Binding and Wiring Hat-Brims, of which the following is a full, clear, and exact description, reference being had to the accompanying drawings, making part of this specification, in which—

Figure 1 represents a plan or top view; Fig. 2, a front elevation. Figs. 3 and 4 are each a sectional elevation, the former on the line A B, and the latter on the line C D of Fig. 1.

The object of this invention is to dampen and prepare the hat-binding material more perfectly and uniformly than has heretofore been done, and thereby to make a great saving in such binding material, as also in time and labor, and to insure more perfect work, and, as a consequence, to produce little or no second quality or inferior finished goods. This invention consists of a damping device composed of a receptacle and retainer for liquid, a saturating or damping roll with an absorbent surface, for absorbing and furnishing liquid from said receptacle, a grooved elastic non-absorbent-surfaced pressure and guide roll, and a guide for the hat-binding material, all the parts being constructed, combined, arranged, and operating as hereinafter described. This invention also consists of a liquid storing and feeding reservoir, in combination with the damping apparatus, said reservoir being of any desired form or proportions, and provided with one or more feeding orifices leading to the connected liquid-receptacle, and an interior air-induction tube with an air-inlet leading from the receptacle to the lower closed end of the tube. This invention also consists of the combination of the described damping apparatus with a hat binding and wiring machine.

In the said drawings, A is the wire-reel, and B the binding-reel, suitably arranged to deliver the wire *a* and binding *b* to a folding device, C, and from this to a pair of pressure-rolls, D, as usual. In order to apply the binding and the wire to the edge of the hat-rim, such sized binding material must be very evenly and uniformly dampened upon the side

which is sized, so as to partially liberate the adhesive substance contained therein, so that when folded and rolled onto the edge of the hat-rim with the wire in the fold, said binding shall instantly adhere to the two sides of the rim, confine the wire, and form a smooth, even finish to the edge of the rim. On the other side of the binding the water must not be allowed to dampen it, as the effect would be to turn the binding white, and destroy the color and finish of the binding on the hat. In the ordinary machine for wiring and binding hats, the binding material is fed loosely over a broad-faced roll running in water. With such a device, by the constant waste of water the supply is proportionately exhausted, and the roll soon fails to bring up a sufficient supply to dampen the binding material properly, and, as a consequence, the binding gradually fails to adhere to the hat-rims, which causes much imperfect work and waste of material; and, besides, the common roll at best dampens the binding very imperfectly, by reason of the edges of the dry stiff binding turning up and running circuitously over the roll, and wetting the upper side of the binding, and when thus unequally dampened the binding will adhere only on certain places, and turns white when damp on the upper side; and this makes further waste and loss of material, time, and labor, even though the water beneath the roll is frequently replenished, and then there is a proportionate failure of dampening and adhesion between the time of replenishing the water and the time of its becoming partially or wholly exhausted. To overcome the aforesaid difficulties, and to insure more perfect work, I provide a water-receptacle, E, which may for convenience be connected with the side of the reservoir F; or the side of one may form the inner side of the other, as shown. Grooved guides *d* are secured to the opposite ends of the water-receptacle, and between these guides I place the journals of a furnishing-roll, H, which has an absorbent surface, and revolves in bearings at the lower ends of the guides *d*, and near the bottom of the receptacle. On the top of the roll H is a grooved guide and pressure roll, I, with a non-absorbent surface,

the roll H entering and revolving in the groove in the top roll, which also has its journals in the guides d. A little to the rear of these rolls, and below or on the line between them, is a slot-guide, f, formed through the back K of the receptacle E. The reservoir F has an open-top air-tube, L, at the side next the water-receptacle. The lower end of this air-tube is closed, except an air-inlet, h, leading to the water-receptacle. At one or both sides of the air-tube inlet, and opening into the water-receptacle, are one or more orifices, g, below the top of the inlet h, and through the end of the reservoir, which is also provided with a filling-inlet, M, and a plug or cover with packing to close it air-tight.

In practice the reservoir is first nearly filled with water, say to nearly the top of the air-tube L, a portion of which water runs through the holes g into the receptacle E, until the water in this is raised above the air-inlet h. The reservoir may then be nearly filled up and the inlet closed. The binding material N, wound on the roll or reel B, passes through the slot-guide f, and between the rolls H and I, with its sized surface against the former roll, and to a folding device, C, where it is folded and receives a wire, m, from a roll or reel, A, and is run onto the rim of the hat between the rolls D, and in its passage from its roll or reel to the finishing-rolls said binding is guided directly from its roll to and over the absorbent-covered furnishing-roll, and beneath the grooved guide elastic and pressure roll, which maintains a uniform pressure on it, and keeps its upper side dry, and it is perfectly and uniformly dampened on its lower side by the saturating surface of the furnishing-roll revolving in water in the receptacle, always at about the same depth, so long as the supply holds out in the reservoir, for when the water in the receptacle is slightly lowered by being carried up on the roll H, the top of

the air-inlet h is exposed, and air enters and passes upward through the open-top tube L into the reservoir above the water, and this allows water to flow through the holes g into the receptacle sufficient to cover the air-inlet and stop further supply of air to the reservoir, and consequent escape of water until again slightly lowered, as before described. While the binding material passes over the furnishing-roll A, it is constantly guided and retained in perfect contact with the surface of the roll H by the grooved guide-roll, which also presses said binding downward, and prevents either edge rising or running off from the saturated surface of the roll H.

I regard the several combinations hereinbefore described both new and useful, and also of considerable value and importance.

I claim as my invention—

1. In combination, an absorbent-surfaced elastic supply-roll, H, a guide and pressure roll, I, a guide, f, and a water-receptacle for damping the binding material, substantially as described.

2. The liquid storing and feeding reservoir F, provided with an open-top air-tube, L, an air-inlet, h, one or more feeding-orifices, g, and a filling-inlet, M, in combination with the receptacle E and rolls H and I, substantially as described.

3. The combination, substantially as specified, of the described damping device, consisting of a water-receptacle, E, an absorbent-surfaced supply-roll, H, and a non-absorbent-surfaced guide and pressure roll, I, with a hat binding and wiring machine.

4. The reservoir F and water-receptacle E, constructed and combined substantially as described.

MRS. DE LANA SHEPLIE.
